UNITED STATES PATENT OFFICE.

JAY O. BALL, OF NEW YORK, N. Y., ASSIGNEE TO SIDNEY BLUMENTHAL & COMPANY, INC., OF NEW YORK, N. Y., A CORPORATION OF NEW YORK.

ART OF COLOR PRINTING.

No Drawing.

Application filed October 23, 1922. Serial No. 596,522.

To all whom it may concern:

Be it known that I, JAY O. BALL, a citizen of the United States, and resident of the borough of Manhattan, in the city and State of New York, have invented a new and useful Improvement in the Art of Color Printing, of which the following is a specification.

The object of my invention is to materially reduce the time, labor, and expense involved in the production of color printing plates.

My new process comprises the making of one or more duplicate plates from an original, as, for instance, duplicate electrotype plates, and the removal of desired portions of the printing faces of the plates, by etching, routing, or otherwise, according to the color or colors to be printed by the plates. This may be accomplished by printing proofs from the original, marking up the proofs for the different portions of the printing faces of the plates to be removed, and using said proofs as patterns for the removal of such desired portions.

As is well-known, the usual process of color printing involves the making of color printing plates by the photo-mechanical process, the so-called negatives from which the color plates are made, being produced by photographic process using color filters.

Certain methods of color printing have also previously been evolved, whereby changes are made in color printing plates of the photo-mechanical process; and that, by means of changing the order of printing the colors from specially made plates, different shadings and gradations in color are secured, as well as so-called wet-printing made possible. Color effects have also been achieved by printing from plates made from the same negative but etched out in different degrees of high lights and shadows to give a photographic effect to the printing.

There is also a process of making multi-color prints from relief tympan sheets built up on the bed of the printing press with the object of accomplishing color printing from only one plate; and certain methods have also been used to vary the lines and dots in the screens, to print out of register, and to simplify the method of color printing so that careful register is not required.

A method of color printing on cloth has also been evolved, whereby one design is

used for a major pattern or key plate and, in the making of subsequent color printing plates, certain portions of the original design are used and certain parts eliminated.

My process is essentially different from any of the above processes in that a very great saving of time, labor, and expense is accomplished. In the usual photo-mechanical process, separate filtration of colors necessitating different negatives and plates for each color is required; or, in the case of color printing on cloth, separate rolls are cut for each color by the same process, while in my process only one original is necessary, which original may be either a half-tone, line drawing, woodcut, intaglio, type face, roller, or other printing surface.

In my process, the duplicate plates may be electrotype plates, either wax or lead moulded, thus producing a material saving in time, labor, and in the expense of materials.

I do not wish to limit myself to the use of only one original plate; for by combining my process with more than one original plate and by doing certain etching and tooling on one or more original plates made from the same negative, new and hitherto unachieved results may be secured, also at a great saving of time, labor and materials over the usual multi-color process.

In the making of the original plate or plates and in the making of the duplicate electrotype or electrotypes for subsequent color printings, I will illustrate two methods of using my process. It will be understood, however, that these two illustrations merely disclose my basic methods of producing plates for color printing, for instance, on paper or cloth, by means of a combination of an original and electrotype, or other duplicate plates made from the original, or a combination of more than one original with one or more electrotype or other duplicate plates.

The two illustrations referred to are as follows:

A. Where one original and one or more duplicate plates are utilized; after one printing plate is made, as for ordinary printing, a duplicate plate and two or more proofs are made depending upon the number of plates to be used. These proofs are then marked for different portions to be removed from the printing faces of the

plates and this removal, as by etching, routing and so forth, is then performed on each desired plate. Etching may also be done by stippling or laying a benday over such parts as may be desired, leaving a printing surface of both plates where a combination of both colors are desired.

B. In the case of two or more original plates and one or more electrotype or duplicate plates, similar methods are followed except that additional fine effects may be accomplished by different etching of the high lights and darkening of the shadows in one or more of the plates.

15 It is apparent that, in either or both of the above illustrations, different combinations are possible, and some objects or parts in the design are made to stand out and others subdued, by varying the etching and routing out in the plates, and by varying the colors and degree of transparency of the inks.

It is evident that variations in the basic principle herein disclosed may be employed 25 within the scope of my invention, both as respecting the character of the plates and the material upon which the printing is done.

What I claim is:

30 1. In the art of color printing, the

method of producing color printing plates comprising, making one or more original color printing plates, making one or more duplicate color printing plates by the molding process from one or more of the original color printing plates, and removing the desired portions of the printing surfaces of said color printing plates to a greater or lesser extent some areas being entirely removed and removing other areas to a lesser degree to print over the impression of another plate or plates.

2. In the art of color printing, the method of producing color printing plates comprising, making one or more original color printing plates, making one or more duplicate electrotype color printing plates from one or more of the original color printing plates, and removing the desired portions of the printing surfaces of said color printing plates to a greater or lesser extent, some areas being entirely removed and removing other areas to a lesser degree to print over the impression of another plate or plates.

In testimony, that I claim the foregoing as my invention, I have signed my name this 20th day of October, 1922.

JAY O. BALL.
